AKE E. SCHONING, OF WOODHAVEN, NEW YORK.

SMOKER'S-PIPE WINDSHIELD.

Application filed March 25, 1924. Serial No. 701,700.

To all whom it may concern:

Be it known that I, AKE E. SCHONING, a subject of Gustavus V of Sweden, and a resident of 1742 Woodhaven Boulevard, 5 Woodhaven, in the county of Queens, city and State of New York, have invented a certain Improvement in Smokers'-Pipe Windshields, of which the following is a specification.

10 This invention relates to smokers' pipe wind shields, and especially that class wherein an arcuate plate is interiorly rifled and adapted to be supported upon the bowl portion of a pipe in either lower inoperative 15 position or raised operative position.

The main object of my invention is to provide smokers with a pipe having a disappearing wind shield adapted for use when lighting the pipe and made interiorly rifled 20 to form the striking surface for a match.

Further objects and attained advantages will appear hereinafter as the specification proceeds.

In the accompanying drawings forming 25 part hereof, Fig. 1 is a view of a pipe furnished with a shield made according to my invention, the shield being in raised operative position.

Fig. 2 is another view of the same with 30 the shield withdrawn in low position.

Fig. 3 is a view of the shield of the former views.

Fig. 4 is a modification of Fig. 1.

Fig. 5 is another view of the same with 35 the shield in withdrawn position.

Fig. 6 is another modification of Fig. 1.

Fig. 7 is another view of the same with the shield in inoperative position.

Fig. 8 is a view of a pipe with an altered 40 shield.

Fig. 9 is a top view of the shield of Fig. 8.

Fig. 10 is a rear view of the shield when the two leaves thereof are joined by a piece 45 of spring steel.

Throughout the views, like reference numerals indicate the same or equivalent parts.

Smokers of all classes frequently find occasion to light their pipes in public places 50 such as on railroad platforms, on the streets and country roads or in other more or less

open places, and therefore, often are annoyed by the wind blowing out their light or match before the pipe has been lighted. In order to overcome this trouble the present invention has been proposed. 55

In the practice of my invention, a pipe 1 having a bowl 2 may be employed and also having the customary fire chamber 3. In the bowl a slot 7 may be cut to form a recess for an arcuate wind shield 4, the lugs 8-8 being adapted to engage the upper portions of the slot similar to 9 on either side to retain the shield in the slot, lug 5 serving as a handle for the shield. 60

The shield is interiorly rifled as at 6 in order to provide a good striking surface for an ordinary match, it being obvious that if the pipe bowl be pointed toward the wind, a match can easily be struck within the 70 shield and remain lighted because of its protection. When thus used, the shield may be depressed into the bowl as in Fig. 2.

In Fig. 4 the bowl has a shoulder 11 and is adapted to carry the shield outside the 75 same, the shield partly enveloping the bowl, especially as noted in Fig. 5. Instead of an upper lug 5, a knob 10 is here provided by which to raise and lower the shield.

In Fig. 6, the slot 7 is simply omitted and 80 the shield inserted in the fire chamber, and Fig. 7 showing the shield depressed.

In Fig. 8, the shield envelopes the bowl 2 and is made of leaves 12 and 15 hinged at 85 13. A spring 16 tends to keep the parts of the shield in good frictional contact with the bowl to prevent the shield from dropping off, while a knob 14 furnishes the grip by which to raise the shield.

It is not necessary to depend on a coil 90 spring similar to 16, but the shield may have its members joined by a piece of spring steel which is riveted to the members and which acts like the spring in clamping the shield on the pipe bowl. It is clear, also, 95 that the shield may be made of one piece as shown in the other views and be resilient throughout for the same purpose.

It is obvious that the principle involved in the shape of the shield is the same in the 100 various views and likewise, the principle of having the shield envelope the light at first

and the fire afterward in all cases, whether in contact therewith or not.

Having thus fully described my invention, I claim—

- 5 A pipe shield comprising an arcuate member adapted to envelope a pipe bowl and including a pair of corresponding curved

leaves hinged together and provided with a spring to close said leaves upon said bowl.

Signed at 132 Nassau Street, in the borough of Manhattan, city and State of New York, this 24th day of March, 1924.

AKE E. SCHONING.
